APPARATUS FOR COILING COMPOUND
TORSION SPRINGS

Friedrich Fuchs, Leitmeritz, Czechoslovakia

Application September 8, 1933, Serial No. 688,602
In Czechoslovakia October 24, 1932

8 Claims. (Cl. 153—65)

This invention relates to a coiling device for the production of so-called stepped or compound torsion springs, composed of a plurality of coaxially disposed spiral springs of different diameters. This device enables the springs to be made economically and independent of human skill. The material is fed by means of a rolling mill, in known manner, and according to the present invention, to a shaping jaw, which coils the material in such a manner as to produce a predetermined diameter and an accurate pitch according to the type and arrangement of the jaw. If now, various jaws of this kind be mounted on a turntable adapted to revolve like a turret, so that, in each case, one of said jaws is brought into position facing the mouth of the rolling mill, the stepped-torsion spring can be coiled from a single strip. In so doing, the material is forced successively against the jaws of different sizes, which impart the corresponding diameter and pitch to the strip, without demanding any special preliminary knowledge in the working of the apparatus. The manipulation is confined to feeding the material, with the aid of the rolling mill, to the smallest jaw in the first place, thus coiling the inmost spring, then turning the turret until the next larger jaw is in the working position, rolling the intermediate spiral spring, and so on, until the entire spring is completed.

In order more clearly to understand the invention, reference is made to the accompanying drawing, which illustrates diagrammatically and by way of example, one embodiment thereof, and in which:

Fig. 1 is an elevation, partly in section, of the rolling mill and shaping jaws on a turntable;

Fig. 2 is a plan view of the apparatus illustrated in Fig. 1;

Fig. 3 is a detail of a compound spring, in vertical section, and produced in the apparatus of the present invention;

Figure 4 is a plan view of Figure 3;

Figures 5, 7 and 9 are details in end elevational of three shaping jaws; and

Figures 6, 8 and 10 respectively, are corresponding side elevations.

The material is fed, by the rolling mill, with the two rollers *a*, through a tapered mouth, into contact with the jaws *d*, *e*, or *f*. The rollers are positively driven by the two pinions *l*, so that the material is reliably fed by turning a crank.

Each of the jaws is shaped and disposed in a

manner corresponding to the desired diameter and pitch of the spring.

The jaws *d*, *e*, *f*, for shaping the springs are semicylindrically recessed. Owing to the elasticity of the strip material, the radius of the semi-cylinder is slightly less than the radius of the spring to be coiled. The jaws are located on such a level that the strip material, which is fed from the rolling mill to the jaws, enters the latter exactly on a level with the lower edge of the semicylindrical recess. In order to facilitate guiding the strip into the jaws, especially in the case of the larger jaws, the semicylindrical recess is chamfered at its lower edge. In correspondence with the pitch of the threads, the jaws are mounted on the turret at a suitable angle, instead of radially. In order positively to guide the springs, the jaws are provided, at the exit side, with small steel plates between which the coiled strip is guided. The two auxiliary jaws *m* and *n*, which effect the transition from one type of helix to another, are of similar design, but these do not require any lateral guide plate, since they have only to shape half a turn of the thread. The rolling mill is fitted with a dividing plate *j* and pointer *k*, which serve for counting the turns of the several springs. The turret *g* is provided with notches and a pawl *h* which, in each case, is caused, by means of a spring *i*, to engage in the notch locking the jaw in working position in relation to the rolling mill. The turret *g* is centered in a baseplate, by means of a pedestal *g*, in known manner.

The operation of coiling is performed in the following manner:

The material *c* is inserted in the taper mouth, and the rolls *a* are turned by a crank and the pinions *l*, so that the strip runs along the hardened jaw *d* and is thereby coiled to form a spiral spring. The number of turns is read off on the dividing plate *j*, and when the desired number is attained, the work is interrupted for the time being. The pawl *h* is swung out and the turret is turned so that the jaw *e* comes into working position, the pawl *h* then again serving to lock the turret. The material is now forced into contact with the jaw *e*, by means of which a spiral spring of larger diameter, and opposite pitch is formed. The same operation is repeated with the jaw *f*. The turret, which may, of course, be provided with a horizontal axis, may be replaced, with equal success, by any other device serving to bring the jaws into position facing the taper mouth of the rolling mill. According to the present invention, in order to simplify bringing the

concentrically disposed springs into coaxial position, auxiliary jaws m and n , against which the material is advanced by the distance of half a thread, are provided between each successive pair of jaws. In this manner a gradual transition from one diameter to the other is obtained. Externally, the auxiliary jaws have the same form as the shaping jaws, but are not provided with a pitch-forming device. The preparation for reversing the (for example) left-handed thread into the right-handed thread is effected in the auxiliary jaws.

I claim:—

1. In an apparatus for coaxially coiling compound torsion springs, a plurality of shaping jaws having segmental cylindrical concave surfaces of progressively different diameters and formed with screw threads alternately of opposite pitch, means for feeding strip material against said jaws, and means for bringing said surfaces of said jaws successively opposite said strip feeding means.
2. In an apparatus for coaxially coiling compound torsion springs, a plurality of shaping jaws having segmental cylindrical concave surfaces of progressively different diameters and formed with screw threads alternately of opposite pitch, a plurality of auxiliary jaws having concave surfaces transitional from one said diameter to another interspaced between said shaping jaws, means for feeding strip material against said jaws, and means for bringing said surfaces of said jaws successively opposite said strip feeding means.
3. In an apparatus for coaxially coiling compound torsion springs, a plurality of shaping jaws having segmental cylindrical concave surfaces of progressively different diameters and formed with screw threads alternately of opposite pitch, means for feeding strip material against said jaws, and a rotatable turret on which said jaws are mounted opposite said strip feeding means.
4. In an apparatus for coaxially coiling compound torsion springs, a plurality of shaping jaws having segmental cylindrical concave surfaces of progressively different diameters and formed with screw threads alternately of opposite pitch, a plu-

rality of auxiliary jaws having concave surface transitional from one said diameter to another interspaced between said shaping jaws, means for feeding strip material against said jaws, and a rotatable turret on which said jaws are mounted opposite said strip feeding means.

5. In an apparatus for coaxially coiling compound torsion springs, a plurality of shaping jaws having segmental cylindrical concave surfaces of progressively different diameters and formed with screw threads alternately of opposite pitch, rolls for feeding strip material against said jaws, and means for bringing said surfaces of said jaws successively opposite said rolls.

6. In an apparatus for coaxially coiling compound torsion springs, a plurality of shaping jaws having segmental cylindrical concave surfaces of progressively different diameters and formed with screw threads alternately of opposite pitch, a plurality of auxiliary jaws having concave surfaces transitional from one said diameter to another interspaced between said shaping jaws, rolls for feeding strip material against said jaws, and means for bringing said surfaces of said jaws successively opposite said rolls.

7. In an apparatus for coaxially coiling compound torsion springs, a plurality of shaping jaws having segmental cylindrical concave surfaces of progressively different diameters and formed with screw threads alternately of opposite pitch, rolls for feeding strip material against said jaws, and a rotatable turret on which said jaws are mounted opposite said rolls.

8. In an apparatus for coaxially coiling compound torsion springs, a plurality of shaping jaws having segmental cylindrical concave surfaces of progressively different diameters and formed with screw threads alternately of opposite pitch, a plurality of auxiliary jaws having concave surface transitional from one said diameter to another interspaced between said shaping jaws, rolls for feeding strip material against said jaws, and a rotatable turret on which said jaws are mounted opposite said rolls.
